DENTAL RETAINER CLASP

Dennis M. Burnett, 6231 Hillside Drive,
El Sobrante, Calif. 94803

Filed Dec. 7, 1970, Ser. No. 26,328

Term of patent 14 years

Int. Cl. D24—02

U.S. Cl. D24—1

FIG. 5

FIG. 2

FIG. 3

FIG. 4

FIG. 6

FIG. 1 is a perspective view of the dental retainer clasp showing my new design.

FIG. 2 is a front view of the dental retainer clasp shown in FIG. 1.

FIG. 3 is a side view of the dental retainer clasp shown in FIG. 1.

FIG. 4 is a rear view of the dental retainer clasp shown in FIG. 1.

FIG. 5 is a plan top view of the dental retainer clasp shown in FIG. 1.

FIG. 6 is a view taken substantially as indicated along line 6—6 of FIG. 3.

I claim:

The ornamental design for a dental retainer clasp, as shown.
